PRIMER VALVE

David S. Williams, Portland, Oreg.

Application December 30, 1933, Serial No. 704,637

9 Claims. (Cl. 182—12)

This invention relates in general to improvements in valves and particularly to primer valves which are automatically actuated by water passing through a standard water supply line and in this manner by-pass some of the water into any trap where water is essential either to act as a gas seal or for any other desirable purpose.

My invention contemplates the use of a primer valve which may be automatically actuated so that water is at all times maintained in floor drain traps, sumps or other analogous contrivances which, either by statutory provisions or by the desire of individuals, require a water seal at all times so that obnoxious gases cannot emanate from the disposal units through the floor drain trap, sump and the like.

The primary object of my invention is to provide means for preventing the emanation of undesirable gases through drains of every sort and description and to provide means for preventing foul water and air to be siphoned into the water supply line.

An important object of my invention is to provide a valve which, when installed directly or indirectly in a water supply line running to or from any service connection, will automatically maintain a predetermined amount of water in a trap, sump or other analogous device so that the same will act as a seal against escaping obnoxious gases and will also compensate for water losses in the trap or sump due to evaporation, leakage or other causes.

A still further object of my invention is to provide a simple, practical, inexpensive and efficient primer valve which may be manufactured at low cost and within a minimum of time.

Another object of my invention is to provide means for maintaining the valve in seated position until the pressure of the water running through the water supply line unseats the valve and permits some of the water to escape and flow into the trap, sump or other analogous device.

An equally important object of my invention is to provide means for automatically by-passing a liquid flowing through a standard supply line into a container which must either be sealed or which may in turn actuate other mechanism such as a fire alarm connected to a sprinkling system.

To attain these and other objects and advantages, I employ somewhat different principles from those set forth in my two co-pending divisional applications for the improvements in "Primer valves", bearing Serial Numbers 714,210

filed March 6, 1934, and 714,805 March 9, 1934, respectively.

Other objects and advantages and the nature and characteristic features of my present invention will become apparent and readily understood from the following description which is to be considered in conjunction with the accompanying drawings forming a part hereof and which illustrate, by way of example, one preferred embodiment of my invention and two modified forms of my improved primer valve, in which:

Figure 1 is a sectional, side, elevational view of a preferred embodiment of my new and improved primer valve illustrated in closed position with respect to the remainder of the valve body.

Figure 2 is a sectional, side, elevational view of the embodiment shown in Figure 1 illustrating the primer valve in open position and indicating the manner of permitting the liquid to enter into the hollow stem.

Figure 3 illustrates a water supply line attached to a standard faucet and which shows one of my primer valves connected to the water supply line and adapted for priming a water trap.

Figure 4 is a fragmentary, side view partially in section, of the valve illustrated in Figures 1 and 2, showing, in addition, a resilient diaphragm interposed between the top of the primer valve and the closure cap of the valve and adapted to normally retain the primer valve in seated position with respect to the upper portion of the hollow stem.

Figure 5 is a top view of the hollow stem, showing the inlets thereto.

Figure 6 illustrates another embodiment of the top of the hollow stem showing the inlets thereto.

Figure 7 is a sectional, side view of a modified embodiment of my invention showing a bell-crank type of primer valve in closed position.

Figure 8 is a sectional, elevational, side view of still another modified embodiment of my invention.

Corresponding parts are identified by the same reference characters.

In carrying out my invention disclosed in the drawings, I employ a valve body herein generally designated by reference character A. The valve body has in general two tubular bores, one extending vertically and the other horizontally with respect to the valve body. The valve body has a boss 1 extending from one side thereof in which is incorporated internal threads 2. A conduit 1A leading from a source of water is threadably engaged to boss 1. Another boss 3, 110

having external threads 4 thereon, extends from the valve body and is in direct opposite alignment with boss 1. A conduit 3A, which is connected to any service outlet or outlets is threadably disposed relative to boss 3. A diaphragm 5 divides the passageway formed between bosses 1 and 2 into chambers 6 and 7. Opening 8 disposed through diaphragm 5 connects the chambers 6 and 7, and port 9 permits the water to 10 drain from chamber 6 to chamber 7 to thereby equalize the pressure within the respective chambers when the water supply is shut off.

Still another boss 10 extends upwardly from the valve body A and has internal threads 11 therein which permit threaded head-cap 12 to be secured thereto. The head-cap 12 has a chamber 13 therein whose function will be described forthwith. Still another boss 14, having external threads 15 thereon, extends downwardly 20 from the valve body A and is in direct opposite alignment to threaded boss 10. A bore or passageway 16 is disposed through boss 14, and said passageway has an internal thread 17 disposed immediately adjacent its upper portion.

25 A hollow stem or supply tube 18 is threadably secured to boss 14 at the thread 17 of passageway 16 and extends upwardly therefrom through chamber 6, opening 8 and chamber 7, and finally has its free end extend into chamber 13 of head-cap 12. A valve seat 19 is either secured to or made integral with the free end 20 of supply tube 18. This valve seat may be constructed as shown in Figure 5, wherein a plurality of openings 21 are disposed therethrough, or the same 30 may be constructed as shown in Figure 6, wherein openings 22 and slot 23 is disposed therethrough. Suffice it to say that each valve seat is constructed with a view in mind of providing sufficient ingress to the water desired to be 40 by-passed from the supply line into supply tube 18.

45 A piston valve, generally designated by reference character B, is slidably disposed about supply tube 18, whose outer surface acts as a valve guide. Piston valve B is composed of a cylinder 24, which has a weighted flange 25 disposed around its outer periphery near its lower end whose function will be described forthwith. External threads 26 are disposed on the oppositely disposed end of the cylinder 24. A valve-cap 27 is threadably disposed around the threaded end of the cylinder 24. A valve-washer made of a resilient material, such as rubber 28, is removably disposed on the ceiling of the valve-cap 27, 50 and said washer is adapted to seal the openings in the valve-seat when the piston valve B is in closed position. It will be noted that a space 29 is disposed between the outside of the supply tube 18 and the inner face of the cylinder 24. 55 By this construction the water coming from the supply source is forced into the space 29 surrounding the outside surface of the supply tube 18 and formed between the supply tube and cylinder 24 for a purpose which will presently 60 appear.

65 A union-connection 30, having a passageway 31 disposed therein, and which is in registerable alignment with passageway 16, is removably secured in a tight fitting connection to the boss 14 by union-coupling 32. A washer 33 serves to prevent leakage between the connection. The free end of the connection 30 has a boss 34 disposed therein with internal threads 35 formed therein. Vent openings 36 and 37 extend through the boss 75 34, and a canopy or vent protector 38 is slidably

disposed about the connection 30 and normally covers openings 36 and 37. It will be seen from Figure 3 that the union-connection 30 may be connected to a drain trap 39. This disclosure, however, should not be considered a limitation of the invention to such use only as the invention is adapted for other uses as well. Attention might well be called to the fact that the vent assembly fulfills several important functions. Not only does the vent assembly permit inspection and supply air to the supply tube, but it also eliminates the possibility of a siphon action taking place between the supply tube and the drain to which the vent assembly is connected. Thus the possibility of foul water and air in the drains being siphoned into the water supply line and contaminating the water therein is entirely prevented.

80 90 95 100 105 110 115 120 125 130 135 140 145 150 The weighted flange 25 normally maintains the piston valve B seated upon the seat 19 so that supply-tube 18 is kept out of communication with space 29. However, it might be found necessary to supply a direct resisting force in order to normally maintain the valve in seated position. Provision is therefore made, as is shown in Figure 4, for a resilient member, such as a rubber diaphragm 40, whose base 41 rests against the ceiling 42 of the head-cap 12, and the apex 43 of the diaphragm normally rests against the top 44 of the valve-cap 27. By this arrangement the piston valve B is forced to return to its seated position when the source of water supply is cut off.

Similar results may be obtained by utilizing a primer valve constructed in accordance with the disclosure shown in Figure 7, wherein reference character C designates generally a valve body embodying a modified form of the invention. Valve-body C has a boss 45 extending outwardly for one of its sides, and said boss has internal threads 46, to which may be secured a conduit, as shown in Figure 3, coming from a source of water. Another boss 47, having external threads 48 thereon, extends outwardly from the opposite side of, and is in direct alignment with boss 45; said boss may have connected thereto a conduit running to any service connection as illustrated in Figure 3. A diaphragm 49 is disposed within the passageway connecting the two bosses, and opening 50 is formed within the diaphragm for a purpose which will presently appear. Reference numeral 51 designates an equalizing port disposed through the diaphragm 49, which is adapted to equalize the pressure within chambers 52 and 53 formed by the diaphragm that divides the passageway as aforesaid. A cylindrical wall 54 extends upwardly from the valve-body C to form chamber 55. The cylindrical wall has internal threads 56, in which is threaded head-cap 57. A bell-crank 58 is movably journaled upon a shaft 59, which is secured to the cylindrical wall 54. Bell-crank 58 has arms 60 and 61. Secured to, or made integral with arm 61 is a weighted disc 62, which normally, because of its weight, has its base 63 adjacent to, but not in contact with side 64 of diaphragm 49. Arm 60 has threads 65, to which is removably secured a valve-cap 66. A valve-washer made of a resilient material, such as rubber 67, is removably disposed on the free end of the valve-cap 66. The function of this bell-crank assembly will be described forthwith.

85 90 95 100 105 110 115 120 125 130 135 140 145 150 Boss 68, having external threads 69, extends outwardly from the cylindrical wall 54. Disposed within the bore or passageway 70 of boss 68 is

and extending into chamber 55, is a hollow stem or supply-tube 71, which has a flange 72 at one end and an opening 73 at the oppositely disposed end. The supply-tube 71 is positioned so that its opening is in registerable alignment with the valve-washer 67, which normally is seated against seat 74 formed at the free end of the supply-tube 71. In this manner, the supply-tube 71 is normally maintained out of communication with the chamber 54; and it is only when the pressure of the water coming from the source of supply swings the weighted disc about shaft 59 that the valve-washer 67 is removed from its seat and permits opening 73 to communicate with chamber 55. A union-connection 75 has its bore 76 in registerable communication with the passageway formed within supply-tube 71 when it is joined to the supply-tube by union-coupling 77. An air vent opening 78 extends upwardly from the union-connection 75 and has a slip-cap 79 disposed thereon with a portion thereof being in spaced relationship thereto to form an air vent as shown at 80.

Equally effective results may be received by a primer valve constructed in accordance with the disclosure shown in Figure 8, which is generally designated by reference character D, and it embodies another modified form of the invention. This valve has incorporated therein the same number of bosses and has connected thereto the same type of union-connection as is shown in Figures 1 and 2. Some changes, however, have been made in the valve mechanism proper. It should be noted that a flange-guide 81 extends upwardly from boss 14 and that boss 14 is removably disposed therein a hollow stem or supply-tube 82. This supply-tube has a flange 83 at one end thereof and an opening 84, which communicates with the hollow interior thereof at its opposite end. A head-cap 85 is threadably secured to the boss 10 and has chamber 86 therein as well as a flange guide 87 at its base. The valve stem 88 has a valve-washer 89, which is removably secured to one end of the valve-stem and is adapted to rest against opening 84 in supply-tube 82. A weighted flange 25 is secured to the valve-stem so that it lies immediately above the diaphragm 5. The stem is guided in its vertical movement by guide-flanges 81 and 87. A supply port 90 is disposed through the flange guide 81, and is adapted to keep a ready supply of water around the supply tube 82, ready to enter thereinto when the valve-stem is raised and opening 84 is uncovered.

Modus operandi

The operation of the valve may now be explained. As indicated in Figure 1, the piston valve is seated on the valve-seat. Assume now that water under pressure is passed into chamber 6. Since water follows the course of least resistance, it will enter space 29 as well as opening 8, and, in so doing, the water will strike flange 25 and raise the piston valve assembly. The opening 21 will then be uncovered so that the water may enter into supply-tube 18. When the water supply is shut off, the weight of the piston valve assembly will force the valve-washer to cover up the openings 21. Figure 2 illustrates the position which the piston valve normally occupies when the water under pressure passes through valve-body. The primer valve illustrated in Figure 8 operates in substantially the same manner.

Similar action takes place when a structure

manufactured in accordance with the disclosure in Figure 7 is used. The water under pressure entering chamber 52 swings the weighted disc 62 so that the water enters chambers 53 and 54, and, when the disc is swung from its normal position, valve-washer 74 is removed from opening 66, thereby permitting the water to enter into supply-tube 71.

This completes the detailed description of the elements applied in my invention, and, from the foregoing description, it will be seen that I have produced valve-mechanisms which substantially fulfill the objects of the invention set forth herein.

While this specification sets forth in detail the present and preferred constructions of the inventions, still in practice deviations from such detail as come within the skill of the mechanic may be resorted to but which do not depart from the spirit of the invention herein. It is to be understood, therefore, that I consider as my own all such modifications and adaptations of the invention as fairly fall within the scope of the invention defined in the appended claims.

Having thus described my invention, what I claim as new and useful and upon which I desire to secure Letters Patent is:

1. In a valve mechanism to be used for the purposes described, the combination of a body member having a plurality of tubular bores therethrough, a diaphragm dividing said bores, and a weighted piston valve vertically movable within said body member, said piston valve adapted to be actuated by the pressure of water passing through the bores.

2. In combination with a water supply passageway, a valve member disposed in said passageway, a diaphragm dividing the interior of said valve member into a plurality of chambers, said diaphragm having an opening therein, a supply tube disposed in said valve member, and a weighted piston valve adapted to sit upon one end of the supply tube when the valve is closed and to be unseated by the pressure of the water passing through said water supply passageway, said weight upon said piston valve adapted to substantially cover the opening in the diaphragm when the valve sits upon said supply tube.

3. In combination, a body member, having an inlet port and an outlet port in direct alignment with each other, a diaphragm interposed therebetween, a supply-tube extending upwardly from the base of the body member and having a plurality of openings therethrough, and a piston valve slidably disposed about said supply-tube, said piston valve adapted to be actuated by water pressure.

4. In combination with a source of water supply under pressure, a primer valve comprising a valve-body member having two passageways each extending through the valve-body and at right angles to each other, a diaphragm dividing said passageways, a supply tube passing through the diaphragm, said supply tube having a valve-seat formed at one end having openings disposed therein, and means disposed about said supply tube and upon said valve-seat for normally maintaining said supply tube out of communication with said chambers, said means adapted for vertical movement with respect to the supply tube upon the application of water pressure thereunder.

5. A primer valve comprising a body member having an inlet passageway and an outlet passageway, a diaphragm, having an opening therein,

disposed between said passageways, said diaphragm having an equalizing port disposed therethrough, a hollow stem vertically disposed with respect to the passageways, said stem having a 5 perforated valve-seat disposed at one end, a piston valve surrounding said hollow stem and having disposed within its ceiling a resilient element adapted to normally seal the perforations in the valve-seat, and a weighted flange disposed about 10 the piston valve, said piston valve adapted to be vertically moved with respect to the valve-stem when a liquid under pressure is permitted to pass through the body member.

6. Apparatus as characterized in claim 5, including a conduit in registerable alignment with the hollow stem, vent openings disposed through said conduit, and a vent protector surrounding said conduit and normally covering said vents.

7. In a device of the class described, in combination, a body member having an inlet passageway and an outlet passageway, a diaphragm disposed between and dividing said passageways into chambers, a supply tube vertically disposed with respect to the passageways and passing through 20 the diaphragm, valve means responsive to the pressure of water passing through the body member disposed within and vertically movable with respect to the body member and guided in its movement by the supply tube, a weighted flange 25 the circumference of which is slightly greater than the circumference of the opening within the diaphragm disposed upon said valve means in

such position as to normally maintain said opening in a substantially covered condition, and a resilient element removably disposed within the body member and positioned in such manner as to offer resistance to the vertical movement of 80 said valve means.

8. In a device of the class described, in combination with a source of water supply under pressure, a body member having an inlet passageway and an outlet passageway, a diaphragm disposed between and dividing said passageways, a supply tube vertically disposed within the body member and passing through the diaphragm, a piston valve responsive to the pressure of water passing through the body member disposed within 90 and vertically movable with respect to the body member and guided in its movement by the supply tube, a resilient element removably disposed within the body member and positioned in such manner as to offer resistance to the vertical movement of 95 said piston valve when said valve is forced to respond to water pressure applied thereunder, and a vent assembly removably secured to the body member in registerable alignment to the supply tube. 100

9. Apparatus characterized as in claim 8, wherein the vent assembly consists of a conduit in registerable alignment with the supply tube, vent openings disposed through said conduit, and a vent protector surrounding said conduit and 105 normally covering said vents.
